Primary Examiner — Darlington Ly*Assistant Examiner* — Katherine A Holbrow(74) *Attorney, Agent, or Firm* — Perkins Coie LLP(57) **CLAIM**

The ornamental design for a mobile display screen with animated graphical user interface, as shown and described.

DESCRIPTION

FIG. 1 is a front view of a first image in a sequence for a mobile display screen with animated graphical user interface, showing our new design; and,

FIG. 2 is a front view of a second image thereof. The broken lines showing the display screen and portions of the graphical user interface form no part of the claimed design.

The appearance of the animated graphical user interface transitions sequentially between the images shown in FIGS. 1 and 2. The process or period in which one image transitions to another image forms no part of the claimed design.
